PHILIP T. JACKSON, OF TORONTO, ONTARIO, CANADA.

HUMIDIFYING ATTACHMENT FOR RADIATORS.

1,418,150.

Specification of Letters Patent. Patented May 30, 1922.

Application filed January 10, 1920. Serial No. 350,609.

To all whom it may concern:

Be it known that I, PHILIP T. JACKSON, of the city of Toronto, in the county of York, Province of Ontario, Canada, have invented certain new and useful Improvements in Humidifying Attachments for Radiators, of which the following is a specification.

This invention relates to devices for increasing the quantity of water vapor held suspended in the air of buildings heated artificially and particularly to devices for use in connection with heating means such as hot water and steam radiators to take advantage of the heat thereof to obtain efficient evaporation, and my object is to devise humidifying means which will be as inconspicuous as possible, which will not occupy any valuable space, and which will possess very high efficiency, and in which the water containers shall be as nearly dust proof as possible.

I attain my object by means of the constructions hereinafter described and illustrated in the accompanying drawings in which—

Fig. 1 is a front elevation of a radiator, partly broken away, provided with my improved humidifying attachment;

Fig. 2 an end view of the radiator partly broken away;

Fig. 3 an enlarged section through one of the troughs of the attachment, and the water supply conduit;

Fig. 4 is a front view of the parts shown in Fig. 3;

Fig. 5 a front view of one of the plates shown for supporting the rod from which the absorbent sheets are hung; and

Fig. 6 a plan view, of the water troughs for a five section radiator and the conduit to which they are connected.

In the drawings like numerals of reference indicate corresponding parts in the different figures.

In the drawings I show a radiator constructed as usual of a plurality of sections 1, such sections being formed of a plurality of loops as shown. 2 is a water distributing conduit, which may be connected with a source of supply in which a constant water level is maintained in any well known manner but which is shown as connected with the water space of the radiator itself to draw its supply therefrom as hereinafter described. This conduit communicates with

the rear ends of a plurality of troughs 3 adjacent their bottoms and is of small diameter relative to the height of said troughs. These troughs are narrow and high relative to their width, their length and other proportions being such that they will extend through from the back or front of the radiator, as the case may be, to a point adjacent the other edges of the radiator sections. The height of these troughs must be small relative to the height of the radiator so as to provide sufficient space above the tops to the troughs for the projection to a suitable height of absorbent sheets as hereinafter referred to.

While any suitable means may be provided to support the conduit and troughs in position as shown above the nipples connecting the radiator sections, at any desired level, I prefer to employ the construction shown comprising an angle bar 4 lying against the rear edges of the radiator sections and a bar 5 fitted between the loops of the sections, said bars running lengthwise of the radiator and being secured together by bolts 6. The bars are thus easily adjusted to vary the vertical position of the troughs and to level up the conduit whenever necessary.

Into each trough dips the lower part of a sheet 7 of suitable absorbent material. Heavy blotting paper, with or without a reinforcement of textile fabric, I find to be suitable for my purpose. If these sheets are heavy enough and not too tall, I find that they may stand unsupported in the troughs with their upper parts extending sufficiently above the same to form evaporating surfaces. These sheets should be in height at least equal to the height to which capillary action will raise the water.

If the sheets of absorbent material are as high as stated and which is necessary to secure a maximum of evaporating capacity, I find it preferable to provide means for hanging them from the upper parts of the radiator sections. I show for this purpose a rod 8 connected with the radiator sections and extending from end to end of the radiator, and hooks 9 secured to the upper ends of the sheets 7. To form a suitable attachment for the hooks, I provide each of the sheets 7 with a metallic reinforcement or binding 10, to which reinforcement the hooks are suitably secured. Each hook is preferably provided with shoulders 11 and 12 at differ-

ent distances from the reinforcement so that each sheet may be held suspended at will in two different positions, either immersed in or just clear of the surface of the water.

5 The shoulders are preferably so positioned that each sheet may be suspended with its lower edge close to the bottom of the trough or with its lower edge raised above the water level in the trough.

10 While the rod 8 may be held in position in any suitable manner, I find the construction shown satisfactory in most cases. The rod passes between two loops of each radiator section and at each outer end is supported by two plates 13 and 14 which lie respectively against the inner and outer surfaces of the end sections of the radiator and are clamped against the same by bolts

15. When the rod 8 is engaged with the lower shoulder of the hook 9 thus holding the sheet free of the surface of the water, the sheet will still be retained between the sides of its trough which thus act as guides when the sheet is lowered to dip into the water. It is desirable to exclude dust as far as possible from the water troughs 3. I therefore contract the sides of each trough adjacent its upper edge as indicated at 18, so that the sides substantially contact with the sides of the absorbent sheet, sufficient space, however, being left to permit of the introduction and withdrawal of the absorbent sheets. As there is a possibility that contact of the upper edges of the trough with the sides of the absorbent sheet might result in water drawn up by the capillary action of the sheets being transferred to the upper edges of the trough to flow down outside the trough, I prefer to outwardly flare the upper edges of each trough as indicated at 19.

To facilitate the introduction of the lower edges of each sheet 7 into the trough, I proportion the free end and the sides of each trough so that the sides extend above the free end of the trough as shown particularly in Figs. 3 and 4. If the lower part of the edge of the sheet be introduced between the sides above the free end, the sheet is readily pushed into position between the upstanding edges and is then readily dropped to its operative position within the trough and supported by the rod 8.

To hold each sheet as far as possible out of contact with the radiator sections, I preferably provide flanges 20 along the lower edges of the metal reinforcement 10 of each strip.

To facilitate the handling of the attachment and to avoid strain on the connection between the troughs and the water conduit, I prefer to connect the ends of the troughs adjacent the conduit by means of a plate 21 to which the troughs are soldered or otherwise suitably connected. This plate

may in fact be an upward extension of an integral sheet from which the conduit is rolled.

In practice variations of the means for supporting the absorbent strips and the troughs with their conduit will be necessary owing to variations in the construction, divisions and arrangement of various radiators, and such variations would fall within the scope of my invention. 75

The conduit 2 is shown as connected with the water space of one of the radiator sections by a pipe 22 in which is located a valve 23, manually controllable or otherwise, by means of which water may be supplied as needed from the interior of the radiator to be evaporated in the humidifying attachment.

What I claim as my invention is:—

1. The combination with a sectional radiator of a humidifying device comprising a water duct; a plurality of substantially parallel narrow troughs each communicating at one end with the duct and adapted to lie between the sections of the radiator 90 above the lower connections thereof, and sheets of absorbent material having their lower parts lying in said troughs and extending above the same between the radiator sections to form evaporating surfaces, said 95 troughs being of small height relative to the height of the radiator, and the height of said troughs also being small relative to the height to which capillary action will raise the water in the sheets. 100

2. The combination with a sectional radiator of a humidifying device comprising a plurality of substantially parallel narrow troughs adapted to lie between the sections of the sectional radiator, said troughs being 105 of small height relative to the height of the radiator; and a tubular duct of small diameter relative to the height of the troughs communicating with each trough at its end adjacent its bottom. 110

3. The combination with a sectional radiator of a humidifying device comprising a water duct; a narrow and relatively high trough communicating at one end with the duct; a sheet of absorbent material having 11 its lower part lying in said trough and its upper part extending above the same to form an evaporating surface, the side walls of the trough extending above one end to permit of the sheets of absorbent material 12 being introduced between the side walls from said end.

4. A humidifying device comprising a water duct; a narrow and relatively high trough communicating at one end with the duct and having fixed side walls; a sheet of absorbent material having its lower part lying in said trough and its upper part extending above the same to form an evaporating surface, the open top of the trough 13

- being formed as a narrow slot substantially only of sufficient width for the passage of the absorbent sheet whereby dust is excluded from the trough.
5. A humidifying device constructed as set forth in claim 4 in which the upper edges of the side walls of the trough are outwardly flared to prevent water from the absorbent sheet passing down outside the walls of the trough.
10. The combination with a sectional radiator of a water duct extending parallel to the length of the radiator; a plurality of narrow troughs each communicating at one end with the duct and extending between the radiator sections, said troughs being of small height relative to the height of the radiator; a plurality of sheets of absorbent material, one for each trough, dipping into said troughs and extending above the same to form evaporating surfaces, the height of said sheets being at least equal to the height to which capillary action will raise the water; a metallic re-inforcement for the top of each sheet; a hook connected to each reinforcement; and a rod supported on and extending lengthwise of the radiator on which said hooks may be hung.
15. A humidifying device constructed as set forth in claim 6 in which each hook is 30 constructed to engage the rod in either of two positions to support the corresponding absorbent sheet with its lower part extending more or less into its trough.
20. A humidifying device comprising a 35 plurality of substantially parallel narrow troughs adapted to lie between the sections of a sectional radiator; a plate to which each trough is attached and which forms one end of each trough; and a tubular duct 40 of small height relative to the height of the plate and connected therewith, said duct communicating with the troughs.
25. A humidifying device comprising a 45 water duct; a narrow and relatively high trough communicating at one end with the duct and having parallel vertical side walls; a sheet of absorbent material having its lower part lying in said trough and its upper part extending above the same to form 50 an evaporating surface, the side walls of the trough adjacent the upper edges thereof being offset inwardly to come close to the sides of the absorbent sheet whereby dust is excluded from the trough.
30. Signed at Toronto this 26th day of December 1919. 55
- PHILIP T. JACKSON.
